UNITED STATES PATENT OFFICE.

CLYDE F. McCANN AND REINHOLD A. BERRENBURG, OF SAN FRANCISCO, CALIFORNIA,
ASSIGNOR, BY DIRECT AND MESNE ASSIGNMENTS, TO PANAMA LAMP & COMMERCIAL COMPANY.

LOCK ATTACHMENT FOR ELECTRIC-LAMP SOCKETS.

Application filed August 17, 1925. Serial No. 50,716.

Our invention relates to lamp sockets, and more particularly to a device for locking an electric incandescent lamp within a socket.

An object of our invention is to provide a fastening means for securing a lamp locking device to a lamp socket.

Another object of our invention is to provide an electric lamp locking device with means adapted to engage a lamp base and 10 prevent unauthorized removal of the lamp from the socket.

Yet another object of our invention is to provide an electric lamp locking device with means to release the locking mechanism for 15 authorized removal of a lamp from the socket.

A further object of our invention is to provide an electric lamp locking device which may be quickly and easily attached to a 20 standard lamp socket without changing the socket structure.

A still further object of our invention is to provide a lamp locking device which is strong and sturdy in construction, consisting 25 of but few parts, and not liable to get out of order even after long and continued use.

Many different types of locking devices have been proposed heretofore for maintaining an incandescent lamp within a socket 30 and locking it against unauthorized removal. Nearly all of these devices require a particular form of key or other unlocking means to release the lamp. Very often after the lamp is locked within the socket, it is necessary to 35 break the lamp before it can be removed. Obviously this arrangement is open to the objection that it may be necessary to remove a lamp for inspection purposes, or other reasons, and it will be found very inconvenient 40 and sometimes expensive to have to break the lamp, particularly if the socket needs repair, or for some reason has to be disconnected from the feed wires.

We have provided a lamp locking device 45 which may be attached to a standard socket, and after the lamp is locked within the socket, the device may be actuated so as to release and remove the lamp from the socket without breaking it or injuring the socket. 50 Our device does not require any special structure for the lamp socket, and it is not necessary to have a key or other unlocking

means, as the device is substantially a combination lock.

With these and other objects in view, which may be incident to our improvements, the invention consists in the parts and combinations to be hereinafter set forth and claimed, with the understanding that the several necessary elements comprising our invention, may be varied in construction, proportions and arrangement, without departing from the spirit and scope of the appended claims.

In order to make our invention more clearly understood, we have shown in the accompanying drawings means for carrying the same into practical effect, without limiting the improvements in their useful applications to the particular constructions, which for the purpose of explanation, have been made the subject of illustration.

In the drawings:

Figure 1 is a perspective view of our lamp locking device attached to a socket;

Fig. 2 is a perspective view of the elements of the locking device in separated position;

Fig. 3 is a vertical sectional view taken through a portion of the socket casing and the locking device;

Fig. 4 is a horizontal view partly in section of the locking device;

Fig. 5 is a detail view of the locking means; and

Fig. 6 is a perspective view of the pawl.

Referring to the drawings, and more particularly to Figure 1, we have shown our lamp locking device attached to a socket. The socket is of a standard form comprising a cap 1 attached to a shell 2 and an actuating key 3 which connects an incandescent lamp 4 in circuit with a suitable source of energy. A locking device 5 is shown attached to the socket and is adapted to prevent unauthorized removal of the lamp from the socket.

Referring more particularly to Figure 2, we have shown the locking device formed of a plurality of concentric annular members, with its various parts or elements separated. The device comprises a cylindrical casing 6 adapted to receive an insulating ring 7, and an insulating band 8 which fit into the cas-

ing 6 and make contact with the sides and top of the casing. The object of the insulating members is to insulate the lock mechanism contained within the casing from the 5 socket shell, which tends to prevent a short circuit between the locking device and the socket parts.

An annular member 9, which we have 10 termed a locking ring, is formed with a spade-shaped member 10 attached to the ring. The member 10 is adapted to be inserted into a socket between the screw receptacle 12 and an insulating material 11 which insulates the receptacle 12 from the 15 socket shell. The receptacle is threaded and adapted to receive the lamp base. The member 10 is concave and flange shaped, it is split longitudinally along lines 10' and is thus formed with three flanges. This arrangement of flanges is provided to securely fasten the ring 9 within the socket and prevent it from being removed therefrom, unless considerable pressure is exerted upon the ring to pull it from frictional contact 20 with the socket casing and the insulated lining 11 of the socket.

When the lamp is screwed into the socket, the upper part rests close to the locking attachment, preventing an unauthorized person 30 from pulling the attachment out of the socket. The frictional engagement of the split spade shaped member with the socket fibre and screw shell prevents the device and therefore the lamp from turning if attempt 35 is made to unscrew the lamp.

The contact between the locking ring and the socket is such that it may be removed by an authorized person for cleaning and inspection purposes without injuring the 40 socket or locking device.

Mounted upon the locking ring 9 are locking means 13 adapted to engage the lamp base and prevent it from becoming unscrewed. An additional annular member 45 14 is provided to engage with the locking ring to release the locking means when it is desired to remove the lamp from a socket. The unlocking ring 14 is provided with projections 15 which engage with the locking means and cause them to release their grip 50 from the lamp base so that the lamp may be released. An insulating band 16 is provided to insulate the unlocking ring and the locking device from a casing 17 which fits 55 down over the locking arrangement and into the ring 6, forming with it a casing for the locking device.

Referring to Figure 3, we have shown a 60 sectional view of our locking device attached to a socket. In this arrangement the elements of the locking device are shown in their respective places when the lock is in the operative position. The pawls 13 are shown in contact with the base 19 of an incandescent lamp.

Referring to Figure 4, we have shown a horizontal view, prong side upward of our locking device attached to a socket. The locking means for engaging the lamp base is shown mounted upon the ring 9. The locking means comprise suitable pawls 13 which are spring actuated and are adapted to be thus pressed against the lamp base. We have shown three pawls in the present arrangement; however, it is to be understood 70 that the number may be varied in order to give the proper contact to retain the lamp within the socket.

Referring to Figure 5, we have shown a detail view of the mounting for the locking means. The dog or pawl 13 is actuated by a spring 20. The spring is mounted upon a projection 21 formed integral with the ring 9 and the pawl is carried by means of a suitable holder or mounting 22 also formed integral with the ring.

Referring to Figure 6, we have shown a perspective view of the pawl or dog. It will be noted that the dog or pawl is bent at an angle and has its contacting points cut and so formed that it will engage with the lamp base and prevent it from being unscrewed 90 from the socket.

The operation of our lamp lock is as follows: An incandescent lamp is inserted 95 through the locking device and the base of the lamp is screwed into a socket. During this operation, the pawls 13 are simply pushed back against the action of the springs and permit the lamp to be screwed into the socket. After the lamp is firmly seated and contact has been made to form suitable electrical connection with the socket, the pawls are released, and it is then impossible to withdraw the lamp from the socket, due to 100 the action of the pawls 13 against the base of the lamp.

In order to release the lock mechanism so as to withdraw the lamp for purposes of renewal or inspection, all that is necessary is to turn the unlocking ring 14 so that the projections 15 come in contact with the pawls and push them back from the lamp base. It will be seen that at this point the lamp then is free to move in the socket and may be unscrewed without interfering with the pawls.

In the present arrangement, the casing 6, the unlocking ring 14 and the casing 17 are crimped together so that they all turn at the same time, and the annular member 9 is held stationary by reason of the frictional engagement of the concave member 10 with the socket screw shell and the insulating lining. In providing a device of this kind, it is unnecessary to have a key or other means to be inserted in order to release the pawls so that the lamp may be unscrewed from a 110 socket.

It will be noted in referring to Fig. 4, that 120 125 130

the three pawls for gripping the lamp base, are spaced unequally (not 120 degrees apart) and the unlocking lugs 15 are spaced to correspond to the pawl spacing so that in turning the unlocking ring, only one special point is found which unlocks all the pawls at one time.

Our locking device is substantially a combination lock, and is easily applied to any existing standard socket and prevents the unauthorized removal of an incandescent lamp from the socket. It is not necessary to change the socket structure in any way in order to attach this locking device, and lamps may be removed from a socket by an authorized person without breaking the lamps or injuring the socket.

While we have shown and described the preferred embodiment of our invention, we wish it to be understood that we do not confine ourselves to the precise details of construction herein set forth, by way of illustration, as it is apparent that many changes and variations may be made therein, by those skilled in the art, without departing from the spirit of the invention, or exceeding the scope of the appended claims.

We claim:

1. A locking device for incandescent lamps comprising an annular hollow casing adapted to fit over a lamp base, means for securing the device to a lamp socket concealed wholly within the socket, an annular member mounted in the casing, locking means for engaging the lamp base mounted upon the annular member, and another annular member within the casing for actuating the locking means.
2. A locking device for incandescent lamps comprising an annular hollow casing adapted to fit over a lamp base, an annular member mounted in the casing, a plurality of flange members attached to the annular member and adapted to engage with a lamp socket, locking means for engaging the lamp base mounted upon the annular member, and another annular member enclosed within the casing and provided with means for actuating the locking means.
3. A locking device for incandescent lamps comprising an annular hollow casing adapted to fit over a lamp base, an annular member mounted in the casing, a concaved flange member for securing the device to a lamp socket, a series of pawls for engaging the lamp base mounted upon the annular member, and another annular member enclosed wholly within the casing provided with means for actuating the pawls.
4. A locking device for incandescent lamps comprising an annular hollow casing adapted to fit over a lamp base, an annular member mounted in the casing, concaved flange members for securing the device to

a lamp socket, a series of spring actuated pawls mounted upon the annular member in spaced relation and adapted to engage the lamp base, and another annular member mounted and enclosed within the casing for actuating the pawls.

5. A locking device for incandescent lamps comprising an annular hollow casing adapted to fit over a lamp base, means for securing the device to a lamp socket, a locking means within the casing for engaging the lamp base, and an annular member enclosed wholly within the casing and provided with projections adapted to depress and release the locking means.

6. A locking device for incandescent lamps comprising an annular hollow casing adapted to fit over a lamp base, an annular member mounted in the casing, a plurality of flange members attached to the annular member and adapted to engage with a lamp socket, a series of pawls for engaging the lamp base mounted upon the annular member, and another concentric annular member enclosed within the casing and provided with means to actuate the pawls to engage and disengage the lamp base.

7. A locking device for incandescent lamps comprising an annular hollow casing adapted to fit over a lamp base, an annular member mounted in the casing, a plurality of flange members attached to the annular member and adapted to engage with a lamp socket, a series of spring actuated pawls mounted upon the annular member in spaced relation, said pawls being adapted to engage with the lamp base, and another concentric annular member provided with shoulder projections to actuate the pawls and release them from engagement with the lamp base.

8. A locking device for incandescent lamps comprising an annular hollow casing adapted to fit over a lamp base, a locking means concealed within the casing for engaging the lamp base, a plurality of flange members carried by the locking means adapted to engage with a lamp socket, and an annular member concealed within the casing provided with means adapted to actuate the locking means.

9. A locking device for incandescent lamps comprising an annular, hollow, rotatable casing, a locking member mounted within the casing, means upon the locking member to secure the locking member to a lamp socket, means within the casing rotatable by the casing for actuating the locking member.

10. A locking device for incandescent lamps comprising an annular, hollow, rotatable casing, a locking member mounted within the casing, means upon the locking member for securing the same to a lamp socket in a fixed position, means mounted within the locking member for engaging the base of a lamp, and an annular rotatable

member rotating with the casing adapted to actuate the locking means mounted in the locking member.

11. A locking device for incandescent lamps comprising an annular, hollow, rotatable casing adapted to fit over and to rotate around a lamp base, an annular locking member mounted within the casing, means upon the locking member for securing the same to a lamp socket, and means carried within the casing to actuate the locking means.

12. A locking device for incandescent lamps comprising an annular, hollow, rotat-

able casing adapted to fit over a lamp base and to revolve thereupon, a locking member 15 mounted within the casing, means carried by the locking member for engaging the lamp base, means carried by the locking member for securing the device to a lamp socket, and means mounted within the casing and rotated thereby to actuate the locking means.

In testimony whereof we affix our signatures.

CLYDE F. McCANN.
